UNITED STATES PATENT OFFICE.

JOHN HORROCKS AND JAMES HORROCKS, OF MANCHESTER, COUNTY OF LANCASTER, ENGLAND.

MACHINE FOR DOUBLING AND WINDING YARN OR THREAD UPON BOBBINS.

SPECIFICATION forming part of Letters Patent No. 313,869, dated March 17, 1885.

Application filed October 19, 1882. (No model.) Patented in England July 19, 1881, No. 3,132.

To all whom it may concern:

Be it known that we, JOHN HORROCKS and JAMES HORROCKS, citizens of Great Britain, residing at Manchester, in the county of Lancaster and Kingdom of Great Britain, have invented certain new and useful Improvements in Machines for Doubling and Winding Yarn or Thread upon Bobbins; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention relates to that class of machines employed for doubling and winding thread commonly known as "drum-winding machines."

In an application for patent filed by us of even date herewith we have shown and claimed certain improvements in devices whereby upon the breakage or absence of a thread the bobbin is lifted clear of the driving-drum.

The present invention is designed as an improvement thereon; and it consists in the combination, with a detector-plate and a bobbin frame or carrier, of mechanism whereby said carrier is held with its bobbin out of contact with the driving-drum, whereby the momentum of the bobbin is arrested, the movement of the carrier in a direction away from the drum limited, and whereby said carrier may be moved into a position relatively to its support with the bobbin out of contact with the latter, substantially as hereinafter fully described.

In the accompanying drawings, Figure 1 is a sectional elevation of a double machine illustrating one construction of bobbin-lifting devices and a modification thereof. Fig. 2 is a like view, on an enlarged scale, of the bobbin-lifting devices shown in Fig. 1. Fig. 3 is a plan view of Fig. 2. Fig. 4 is a sectional elevation of a modification in the construction of the bobbin frame or carrier shown on the right of Figs. 1 and 2 and on the left of Fig. 3. Fig. 5 is a like view showing the bobbin frame or carrier of Fig. 4 lifted clear of the driving-drum and lever-frame. Fig. 5^a is

a perspective view of the brake lever D shown in Figs. 4 and 5. Fig. 6 is a sectional elevation of a further modification in the construction of the bobbin-lifting devices. Fig. 7 is a plan view thereof. Fig. 8 shows another modification of the said bobbin-lifting appliances. Figs. 9, 10, 11, and 12 are detail views of an improved detector-plate, and Fig. 13 is a detached view showing the mode of pivoting the detector-plate.

Like letters of reference indicate like parts wherever such may occur in the above figures of drawings.

A, Fig. 1, indicates the main frame, of any suitable material, and constructed to support the operative mechanism, and in order that this latter may be better understood we will first describe that construction shown on the right of Figs. 1 and 2 and on the left of Fig. 3.

C indicates the driving-drum, and H the bobbin, the spindle h of which rotates in bearing-grooves b³, formed in the side bars b of a frame or carrier, B, one of which side bars is extended to form a handle, B³. The side bars b are connected together at their rear ends by a cross-bar, B², provided on its under side with bearings in which is secured a pivot-pin, b', upon which is pivoted the rear end or long arm of an angular lever, D, that has its fulcrum at d' in a bracket, a, attached to the beam A', that extends from end to end of the machine. The lever D is composed of two angular side bars, forming short and long arms on the inner and outer side of the fulcrum d', respectively. The side bars d on the inner side of the fulcrum, which constitute the short arm of the lever D, are connected by a cross-bar, d², a like cross-bar connecting said arms on the outer side of the fulcrum d', as plainly shown in Figs. 2 and 3.

Upon the pin b', between the arms d of lever D, is pivoted a tripping-lever, F, composed of the socketed shank f and the pin f', adjustable within the socket of the shank by means of a set-screw, f². The free end of the tripping-lever projects outwardly, and is adapted to bear against a stop, e, that projects from the detector-plate E, and lies upon the upper face of the beam A', in which said plate E is pivoted. The side bars b of the bobbin frame or carrier may be weighted in any suit-

able manner. We preferably provide these bars with means—such as the holes b^2 , or equivalent means—for attaching a weight, b^4 , thereto, by means of a cord, as shown, or by means of 5 a link or chain. When during the winding one or more threads break or is or are absent, the corresponding detector wire or wires drop down into the path of a cam-shaft or a prism-shaped shaft, G, (preferably the latter.) This 10 shaft, impinging upon the lower end of the detector wire or wires, tilts the detector-plate E, its stop e being moved out of the way of the tripping-lever F to release the carrier and lever. Both the carrier B and lever D are 15 now free to swing on the fulcrum d' , the inner ends of the lever D descending to meet the bobbin-carrier and support the bobbin, and at the same time act as a brake to arrest the momentum of said bobbin. This movement of 20 the lever D and bobbin-frame is greatly accelerated by the action of the weight b^4 , so that the bobbin is rapidly carried out of contact with the driving-drum to enable the operator to find and tie the broken or absent 25 thread or threads, as hereinafter explained, and at the same time said weight not only holds the bobbin firmly on the drum while in contact therewith, but also holds said bobbin firmly on the lever, and assists in checking or 30 arresting its momentum.

By an inspection of the drawings it will be seen that the bobbin-carrier is pivoted to the long arm of the lever D, and that the latter has its fulcrum at d' . Hence, if the tripping-lever is released, the bobbin-carrier B will 35 move outwardly or away from the drum, and downwardly, while the outer end of the lever D moves downwardly and its inner end upwardly against the bobbin, for the purposes set forth, 40 the bobbin resting upon the lever end d' .

Upon the pin b' , between the arms d of the lever D, is hung a flat leg or stop, B', the pin passing through a vertical slot, b^5 , in said stop.

When the carrier and lever are tilted, as 45 above described, to carry the bobbin away from the driving-drum and support it in that position, the lower face of the stop B' comes in contact with the bracket a , and its upper face with the under side of the cross-bar B^2 , thus limiting the downward movement of the 50 carrier and lever, and supporting the same in the proper position.

To enable the attendant to hold the bobbin out of contact with the lever and rotate the 55 same to find the broken or absent thread or threads, when said lever and carrier have been tilted as described he depresses the handle B^3 of carrier B, thereby elevating the bobbin clear of the end d' of the lever D. In this movement of the carrier B the cross-bar B^2 thereof slides over the outer upper corner of the stop B', downwardly a short distance, and carries with it the short arm of lever D and pin b' , which latter moves down in the slot of the 60 stop B' a short distance, the cross-bar of the carrier bearing against the edge of the stop, which thus affords a certain but small amount

of leverage to support the carrier. This leverage and the frictional contact of the cross-bar with the stop hold the carrier up with the 7c bobbin out of contact with the lever, but not so securely that by applying a certain amount of force to the handle the carrier cannot be returned to its normal position. In this movement of the carrier with the lever the bobbin is carried away from the latter, owing to the difference in the distances traveled by the short arm of the lever and the longer side bars of the bobbin-carrier. This downward movement of the pivot-pin b' and lever D in the 80 slot of the stop will be readily understood when it is borne in mind that the stop B', when in contact with the bracket a , constitutes the support as well as the fulcrum from which the bobbin-carrier B is supported and upon which 85 it can be tilted, and inasmuch as the pivot-pin b' for the long arm of the lever D passes through a slot in the stop, and the outer end of both the bobbin-carrier and lever can move downward when the carrier is tilted in the 90 stop B', the pin will necessarily partake of this downward movement in the slot of the said stop, which movement is, however, a limited one, but sufficient to afford a bearing to hold the bobbin-carrier with the bobbin away from 95 the lever D, as above stated. When the absent or broken thread or threads have been 100 found and tied, and it is desired to return the bobbin in contact with the driving-drum, the attendant lifts the carrier B by means of the handle B^3 , the pin b' rising in slot b^5 of the stop B' until the cross-bar B^2 of carrier B again lies on the upper face of said stop B' and the bobbin on the end d' of lever D. By a slight 105 further movement of carrier B in the direction of the drum C the stop B' is lifted clear of the bracket a , and the carrier and lever will swing 110 toward the drum sufficiently to cause them to continue to move in that direction by their own weight or by the latter assisted by the weight b^4 .

Instead of supporting the bobbin-carrier B and lever D upon the stop B', they may be supported as shown in Figs. 4 and 5, wherein one of the side bars b of the bobbin-carrier 115 B has an outwardly and downwardly projecting extension or arm, B^4 , and upon the outer face of the transverse bar B^2 of the carrier at its outer end are formed bearing-lugs, Figs. 2, 3, 6, 7, and 8, in which is secured the pivot-pin b' . Upon this pin is pivoted the tripping-lever F, the arm f' of which extends rearwardly and bears against the tripping-arm e of the detector-plate E. As shown, this arm 120 is made tapering, for purposes presently explained.

The lever D is pivoted upon a bracket, a , and is constructed as follows: The inner short arm, d^2 , of the lever has a bearing-surface, d^6 , upon which the bobbin is supported when 130 moved out of contact with the driving-drum. d^7 are depending lugs constituting pivotal bearings, by means of which it is pivoted to bracket a . The outer or longer arm of the

lever D is formed by two diverging arms, d^5 , having lugs d^8 , projecting vertically therefrom and forming bearings, by means of which the said longer arm is pivoted to the outer 5 end of the bobbin-carrier by means of the pivot-pin b' . One of the lugs d^8 has arms D^3 d^3 , as plainly shown in Fig. 5^a, projecting vertically therefrom, the former serving as a handle and the latter as a rest or foot for supporting the lever and bobbin-carrier when the latter has been tripped.

The operation of these devices is plainly illustrated in Figs. 4 and 5, and may be briefly described as follows: When the parts are in 15 their normal position, as shown in Fig. 4 in full lines, the bobbin is in contact with the driving-drum, held there by its own weight or by said weight b^4 and an additional weight suspended from the carrier at b' ; but said bobbin is not in contact with the bearing-surface 20 of the lever. When a thread or threads break or are absent, and the detector wire or wires thereof fall into the path of the rotating angular bar G, the detector-plate E is tilted upward and its arm e moved away from the arm f' of the tripping-lever F, thus allowing the 25 bobbin-carrier B, and with it the lever D, to swing on the pivot of bracket a, the inner arm, d^2 , of the lever rising to meet the downwardly-moving bobbin and support the same.

It is obvious that since the carrier B is pivoted at its outer end only to or with the lever D the inner end thereof, through the bobbin, is supported clear of the inner end of the lever D by the driving-drum, and that, as soon 35 as said carrier moves outward and away from the drum, the bobbin moves downward until, when clear of the drum, it meets and is supported by the upwardly-moving lever end or bearing-surface d^6 . The lever D, being pivoted about its longitudinal center, can therefore only swing downward on its pivot, and as its outer end swings downward its inner end necessarily swings upward to meet the 40 downwardly-moving bobbin. In this manner the bobbin is not only supported by the end of lever D, but the extended bearing-surface d^6 thereof acts as a brake to arrest the momentum of the bobbin. The downward motion 45 of the outer end of the carrier and lever is limited by the extension or foot d^3 coming to rest upon the beam A^2 , which extends or may extend from end to end of the machine, the bobbin being thus held out of contact 50 with the driving-drum, as shown in dotted lines in Fig. 4. In this downward movement of the outer end of carrier B the arm f' of the tripping-lever passes under the arm e of the detector-plate E, and as said arm increases in 55 thickness from its end to the plate, the latter is tilted to such an extent as to move the detector-wires out of the path of shaft G, as shown in dotted lines, Fig. 4.

To enable the attendant to rotate the bobbin 65 and find and tie the broken or absent thread or threads, he lifts the carrier B until the inclined arm B^4 has passed over the beam A^2 ,

during which movement of the arm the carrier and lever are slightly lifted or tilted on their respective pivots, and when said arm 70 has passed over the beam the carrier and lever again drop down, the arm bearing against the vertical face of the beam and holds the carrier in the position shown in Fig. 5. To return the parts into their normal position, 75 the attendant lifts the lever D, and with it the carrier, by means of the handle D^3 until the arm B^4 is clear of the beam A^2 , when both lever and carrier will swing forward on their pivots, and said parts will then be in the position shown in dotted lines, Fig. 4. By lifting the carrier on pivot b' , and then tilting the inner end of the same and that of the lever D downward until the arm f' of lever F bears 80 against the arm e of detector-plate E, and allowing the carrier to drop, the bobbin will again lie on the driving-drum, as shown in full lines, Fig. 4.

We will now describe that construction of mechanism shown on the left of Figs. 1 and 2 90 and on the right of Fig. 3. In this construction the bobbin-carrier B is pivoted upon a fulcrum or axis, b' , that has its bearings in two arms, a^2 , pivoted at a^3 in bearings a^4 , secured to the beam A^2 , that extends from end 95 to end of the main frame.

Upon the pivot-pin b' is pivoted the tripping-lever F, constructed substantially like the lever described hereinbefore, the outer or free end of which abuts against a tripping-arm, e, secured to and projecting from the detector-plate E, the outer end of said arm lying upon the beam A^2 , as shown.

Upon the beam A^2 is secured an inclined flat plate, I, that extends under the bobbin H 105 in proximity to the driving-drum C, and is of such a width as to adapt it to perform the functions of a brake to arrest the momentum of the bobbin when the carrier B descends to carry the bobbin onto said plate.

As shown in Fig. 1, the bobbin is held in contact with the driving-drum, and is rotated thereby to wind the threads; but when a thread breaks or is absent its detector-wire falls and comes in contact with the cam-shaft 115 G, that causes the detector-plate to swing upward, thereby lifting the arm e away from the tripping-lever F, which slides under said arm and allows the carrier B to swing toward said plate E or upward, the bobbin H riding 120 over the driving-drum onto the fixed brake-support I. Here, as in the construction shown on the right of Figs. 1 and 2 and on the left of Fig. 3, the tripping-lever slides under the tripping-arm e of the detector-plate and causes said plate to move farther away from the prism-shaped shaft or bar G, by which movement the detector-wires E' are carried out of the path 125 of said bar.

As shown in Figs. 1 and 2 on the right, the arm e may be arranged at a desired angle to the plate E to effect this additional movement of the latter; or said arm e may be bent at right angles to the plate, as shown on the left

of said figures; or, as shown in Figs. 4 and 5, it may be wedge-shaped or made tapering from the plate outwardly. Any one of these arrangements may be adopted to insure the removal of the detector-wires from the path of the angular bar G after the plate has been tilted by the latter.

As shown on the left of Figs. 1 and 2, the outward movement of the carrier B is effected 10 by the weight of the bobbins and that of the free end of the carrier, or by said weights and the attached weight b^4 , and as soon as the lever F is tripped the arms a^2 under the weight described rotate outwardly on their pivot a^3 , carrying with them the carrier B, which at 15 the same time swings downwardly on its fulcrum b' . This downward and outward movement causes the bobbin to roll off the driving-drum C onto the inclined supporting brake- 20 plate I, that holds the bobbin and carrier, and by reason of the weight alluded to at once arrests the momentum of said bobbin.

Upon the fulcrum a^3 is hung a leg or stop, J, the lower end of which extends downward 25 in front of the beam A^2 . When the bobbin-carrier is tilted outwardly upon the breakage or absence of a thread through the operation of the detector-plate and tripping devices, the cross-bar B^2 impinges against the upper edge 30 of the leg and tilts the same outward, the carrier being held in this position by gravity or by the latter and the additional weight b^4 . When so tilted outward, the longitudinal axis 35 of the leg J lies nearly parallel with the upper face of the beam A^2 , and the cross-bar B^2 of the carrier B above and slightly in front of the pivot a^3 . By lifting the carrier by means 40 of the handle B^3 sufficiently to allow the leg J to swing inward into the vertical position the cross-bar B^2 of the carrier will come to rest 45 upon the leg, and said carrier will be held in a sufficiently elevated position to hold the bobbin clear of the brake-support I and enable the attendant to rotate said bobbin and find and tie the broken or absent threads. By pushing the handle B^3 inward the cross-bar B^2 of the carrier will slide over the upper 50 face of the leg J, its inner end dropping down with the bobbin on the brake-surface I. The carrier may now be lifted sufficiently to bring 55 the tripping-lever F against the tripping-arm e of the detector-plate E and allowed to drop, and the bobbin will again lie on the driving-drum, with the extension a^5 of one or both arms a^2 below their pivotal connection a^3 , bearing against the vertical face of the beam A^2 , as shown by dotted lines on the left of Fig. 2 and in full lines in Fig. 6.

As shown in Figs. 6 and 7, a bent wire, D^2 , 60 connected with an arm, a, projecting from the arms a^2 of the carrier B, and a horizontal wire supported from the detector-plate, as described in the Letters Patent hereinbefore referred to, may be employed instead of the tripping-lever 65 and arm for tripping the bobbin-carrier, and instead of a bent wire, D^2 , a straight wire may be employed, said wire being held by a verti-

cal tripping-arm, e, projecting from plate E, as shown in dotted lines, Fig. 6.

Instead of the construction of bobbin-carrier and tripping mechanism therefor hereinabove described, the construction of carrier and tripping mechanism shown in Fig. 8 may be employed, and this will be found equally efficient. This mechanism is similar to that 70 shown on the left of Figs 1 and 2 and on the right of Fig. 3, except that the bobbin H is suspended between the detector mechanism and the fulcrum b' of the bobbin-carrier B. In this arrangement two bobbins may also be 75 wound upon opposite sides of the driving-drum, although we have shown but one, and this construction is equally if not more conveniently applied when only one bobbin is wound. In said construction a beam, A^3 , extends the full length of the machine above the drum C, and carries brackets A^4 for the operative mechanism. The arms a are pivoted at a^3 upon the bracket A^4 , and the side bars b of the carrier B are pivoted to said arm at 80 b' . One of the arms, a , is extended to form a handle, B^3 . From the side bars of the bobbin-carrier project arms b^6 , to which the weight b^4 is attached, to press the bobbin against the periphery of the driving-drum C; and F is a 85 tripping-lever or bar pivoted upon the carrier-fulcrum b' , and abutting against the tripping-arm e, secured to the detector-plate. A notched stop, J, is pivoted on a pin attached to one of the side bars b of the carrier B. 90 The stop has a stud or projection, j' , that limits its downward movement by coming in contact with the edge of one of the side bars b . When the bobbin-carrier is released by the tripping devices, as described, and descends, the notch 95 j' engages the wedge-shaped projection or spur k' , formed on a bracket, K' , to support the carrier and hold the bobbin clear of the drum on the inclined brake-support I. When the momentum of the bobbin has been arrested, the 100 bobbin-carrier may be raised until the nose j^2 of the stop J rests upon the end k^2 of the spur k' on bracket K' , when the bobbin will be clear 105 of the brake I, and may be rotated to find and tie the broken or absent thread end or ends. 110 When the bobbin-carrier is moved back by the handle B^3 , the end of the stop slides off the spur k' , leaving the carrier free to swing in 115 toward the driving-drum C, and carry the bobbin into contact therewith.

As shown by Figs. 9, 10, 11, and 12, which illustrate the detector-plate by an edge view, front, and elevations, and a vertical transverse section, respectively, said plate E has a trunnion or pivot, e^4 , and a projecting lug 120 or stud, e^5 , at each end, instead of a pivot only, as described in our Letters Patent hereinabove referred to. When the plate E is hung in its bearings formed in arms A^6 , that project from the beams A^1 A^2 , the pin e^5 lies 125 under said bearings, and thus locks the plate against vertical movement, leaving it free to swing in the direction of the drum, which movement is not sufficient to clear the pins e^5 from

- under said bearings, a half-turn of the detector-plate being required for the latter purpose, when the detector-plate may be lifted out of its bearings, as shown in Fig. 13.
- 5 Instead of the locking pins or studs e' , the plate may be provided at each end with a curved arm, e^6 , that extends rearwardly under a lug or projection, a^x , formed on the outer face of the bearings for the plate E and immediately above the curved arms e^6 , as shown on the right and left of Figs. 2 and 3, respectively, and in Figs. 6 and 7. In this manner the detector-plate is held against vertical displacement, though free to swing toward the driving-drum, as described. This movement is, however, not sufficient to effect the displacement of the detector-plate from its bearings, a half-turn toward the drum being required to permit its removal therefrom, the same as with 15 the locking-studs above described. The detector-plate is provided with longitudinal ribs e' , notched or channeled, as at e^2 , for the passage of the wires E', which wires have a curl or are bent, as at e^3 , to prevent their being 20 lifted out of the plate by the tension of the thread, and also to hold said wires against tension. The wires are held in their notches by a retaining-plate, E ^{2} , secured to plate E by a thumb-screw, E ^{3} .
- 25 30 The threads to be doubled or wound are drawn from cops or from bobbins or swifts arranged in any ordinary manner. Said threads pass each through a slit in a cleaning or guide plate, K, and over a flannel-covered tube, L, to give friction and clean the threads. From the tube the threads pass through the guide hooks or curls e^x of the detector-wires E', thence 35 over the pulleys M, mounted in bearings formed in arms m , secured to the upper beam, 40 A ^{3} , of the main frame A. From the pulleys M the threads descend through guide-loops n , adjustably secured to a bar, N, that has the usual traversing motion for distributing the threads, from which guide-loops said threads 45 pass onto the bobbins, all as plainly shown in Fig. 1.
- Having now described our invention, what we claim, and desire to secure by Letters Patent of the United States, is—
- 50 1. The combination, with a driving-drum, a bobbin-carrier, a stop to hold the latter with its bobbin in contact with the former, and tripping devices to trip the stop and permit the carrier to move away from the drum, of a sup-
- port for the bobbin and carrier acting to stop 55 the rotation of the bobbin, and devices to hold the said carrier with its bobbin out of contact with the support and the driving-drum, substantially as and for the purpose specified.
2. The combination, with a driving-drum, a 60 bobbin-carrier, and a stop to hold the latter with its bobbin in contact with the former, of a detector-plate, detector-wires, a rotating shaft to oscillate said plate when a wire drops on the breakage or absence of a thread to trip 65 the stop and permit the bobbin-carrier to move away from the driving-drum when the detector-plate is tilted, a support for the bobbin and carrier operating to stop the rotation of 70 said bobbin, said carrier being constructed to take a position with its bobbin out of contact with the support, substantially as and for the purpose specified.
3. The combination, with a driving-drum, 75 a bobbin-carrier, a stop to hold the latter with its bobbin in contact with the former, and tripping devices to trip the stop and permit the carrier to move away from said drum, of a lever connected with and forming the fulcrum for said carrier, and constructed to support 80 the same and act as a brake for the bobbin when said carrier has moved away from the drum, as described, for the purpose specified.
4. The combination, with a driving-drum, a 85 bobbin-carrier, a stop to hold the latter with its bobbin in contact with the former, and tripping devices to trip the stop and permit the carrier to move away from the drum, of a brake connected with and forming the fulcrum for 90 said carrier, and means to limit the movement of the carrier and brake in a direction away from the drum, substantially as and for the purpose specified.
5. The combination, with the frame having 95 the arms A ^{6} , provided with semi-cylindrical bearings, of the detector-plate E, having journals e^1 lying in said bearings, and projecting lugs e^2 at each end adapted to engage the under side of the journal-bearings, substantially as described, for the purpose specified.

In testimony whereof we affix our signatures in presence of two witnesses.
